UNITED STATES PATENT OFFICE.

WILLIAM J. POOLE, OF HIGH SHAWLANDS, SCOTLAND.

STEAM-TRAP.

SPECIFICATION forming part of Letters Patent No. 735,294, dated August 4, 1903.

Application filed February 24, 1903. Serial No. 144,754. (No model.)

To all whom it may concern:

Be it known that I, WILLIAM JOHN POOLE, a subject of the King of Great Britain and Ireland, and a resident of 19 Waverley Park, 5 High Shawlands, in the county of Glasgow, Scotland, (whose postal address is 19 Waverley Park, High Shawlands, Glasgow, Scotland,) have invented certain new Improvements in and Connected with Steam-Traps, 10 (for which I have applied for a British patent, No. 17,281, dated August 6, 1902,) of which the following is a specification.

My said invention relates to steam-traps of the type in which is used an inverted bell 15 having a central guiding-spindle, and has for its object to improve the construction of such steam-traps so that the opening of the discharge-valve will not depend merely on the weight of the bell when the water of condensation overflows thereinto, as is usual with 20 this class of steam-trap, but will be controlled by the action of the fluid on a piston part connected to the discharge-valve, the supply of the fluid to this piston being controlled by 25 a small valve actuated by the float.

My invention also comprises means whereby the valves are kept tightly on their seats in order to insure that the bell shall not be emptied by leakage past the valves when 30 they are closed.

My present invention is preferably applied in connection with steam-traps provided with the improved device for causing the valves to grind on their seats after closing as described in my patent specification Serial No. 35 73,074.

In carrying out my invention in the case of a steam-trap such as is shown in vertical section in the accompanying sheet of drawings there floats in the water of condensation in the trap A the usual inverted bell A', having attached to it in the usual manner a central spindle A²; but instead of this spindle carrying the usual discharge-valve it has on 40 its upper end a small valve A³, hereinafter termed a "pilot-valve," controlling a passage B, formed through a main discharge-valve B' and communicating with the upper end of a cylinder B², in which works a piston B³, 45 connected to the upper end of the discharge-valve B', but of larger area than such

valve. The central spindle A² is guided by vanes C thereon, bearing on the inner side of a tube C', attached to and extending down from the discharge-valve B' into the bell A'. This tube C' is not rigidly fixed to the main discharge-valve B', but is attached thereto by loosely-fitting screw parts and locking-pins C², so as to give a slight amount of flexibility to the joint, so that any want of alignment of the inner tube C' or outer main discharge-pipe C³, hereinafter referred to, shall not prevent the main discharge-valve B' from closing tightly on its seat D, and also shall not prevent the tube C', valve B', and 55 piston B³ from together revolving and moving vertically, as hereinafter described, with the minimum amount of friction. The tube C' has on its outer side vanes D', which bear on the inner side of the main discharge-pipe C³, dipping into the bell A', and the tube has also on its lower end a weighted ring or fly-wheel D⁴ for a purpose hereinafter described.

When the inverted bell A' is in its highest position, the pilot-valve A³ and the discharge-valve B' are both closed by the buoyancy of the bell and the pressure of the fluid on the tube C' and discharge-pipe C³. When the bell A' sinks, the small valve A³ is opened, and water rising through the tube C' flows through 60 the passage B in the discharge-valve B' into the cylinder-space B² above the piston B³. The upper side of the piston B³ and the lower side of the discharge-valve B' are now under approximately the same pressure; but the area 65 of the piston being greater than that of the discharge-valve the latter is forced downward, and the fluid then escapes up the main discharge-pipe C³ and through the opening controlled by the main valve into the discharge 70 D². When the piston B³ has moved down the requisite distance to open the discharge-valve B', this movement uncovers a relief-port D³, extending from the cylinder B² to the discharge D², and when the relief-port is opened 75 the supply of fluid through the small passage B is not sufficient to maintain the pressure in the cylinder-space B² above the piston B³ necessary to overcome the pressure tending to close the discharge-valve B'. The piston 80 B³ therefore moves upward again until the relief-port D³ is partly closed and a state of 85

equilibrium reached between the pressures on the lower side of the discharge-valve B' and the upper side of the piston B³. When the bell A' is partly empty, it rises sufficiently 5 to close the pilot-valve A³ on its seat and so cut off the supply of fluid to the cylinder B², and as the piston B³ is not a close fit in the cylinder the pressure therein falls, owing to leakage, past the piston. As the fluid thus 10 escapes from the cylinder B² the piston B³ rises, owing to the combined action of the pressure on the lower side of the discharge-valve B' and the buoyancy of the bell A', and the discharge-valve is brought to its seat. 15 In steam-traps of this type if the discharge-valve B' or even the pilot-valve A³ should from any cause be kept from closing tightly on their seats the steam-pressure in the trap causes the water which should otherwise 20 gather in the bell A' to siphon out past either the leaky main discharge-valve B' or in the case of the pilot-valve A³ past that valve and past the piston B³, the latter not being a tight fit, and owing to this leakage the bell 25 A' does not fill and sink, as it should do. To overcome this defect, I form a small opening E not only through the discharge-pipe C³, but also another similar opening E' through the inner tube C', these openings being below 30 the valves. By this means I obtain equilibrium of steam-pressure in the bell A' and in the discharge-pipe C³ and tube C' above the level of the water therein. This prevents the water rising in the discharge-pipe C³ or 35 in the tube C' and allows it to gather in the bell A' until its weight is such that the bell sinks, as usual. The size of the openings E E' must be considerably smaller than the 40 passages controlled by the valves A³ or B', so as to prevent the possibility of the steam-pressure in the discharge-pipe C³ or in the tube C' interfering with the free action and discharge of the water of condensation once the bell does descend, as hereinbefore 45 described. The guiding-vanes C D' are so constructed and held that when the water of condensation is being discharged, as described, not only will the bell be revolved as it empties and rises, as described in my patent specification Serial No. 73,074, but also the tube C', 50 attached to the discharge-valve B' and carrying the fly-wheel D⁴, the vanes C D' being so carried that these parts and the two valves A³ B' rotate in opposite directions, the piston 55 B³ also rotating with the valve B'. When the valves have reached their closed positions again, the momentum which the bell A' and the fly-wheel D⁴ have gained will make both 60 valves turn on their seats more or less and insure the desired grinding action being obtained.

What I claim as my invention is—

1. A steam-trap, having a discharge-pipe, a main discharge-valve and a piston controlling the outlet from such pipe, a pilot-valve 65 opening into a normally closed chamber, the piston working in said chamber, and an inverted bell to control the movements of the discharge-valve and piston, substantially as described.

2. A steam-trap having a discharge-pipe, a discharge-valve and a tube attached thereto within the pipe, a piston on such valve, a cylinder in which the piston works, a relief-port from the cylinder, a passage through 75 the valve and piston, a pilot-valve controlling the passage, a spindle carrying the pilot-valve and an inverted bell attached to such spindle, substantially as and for the purposes described.

3. A steam-trap, having a discharge-pipe, a main discharge-valve and a piston controlling the outlet from such pipe, a pilot-valve opening into a normally closed chamber, the piston working in said chamber, and an inverted bell to control the movements of the discharge-valve and piston, in combination with means for rotating the valve so arranged 85 that the passage of fluid against them during discharge will rotate the valve, whereby it is 90 caused to grind on its seat upon and after closing, substantially as described.

4. A steam-trap having a discharge-pipe, a main discharge-valve and a piston controlling the outlet from such pipe, a cylinder for 95 the piston, a relief-port from the cylinder and a passage through the valve and piston, a pilot-valve controlling the passage, a tube attached to the discharge-valve and extending down within the discharge-pipe, a spindle 100 carrying the pilot-valve, an inverted bell attached to the spindle, and a small opening formed through both the tube and discharge-pipe below the level of the valves, substantially as and for the purposes described.

5. A steam-trap having a discharge-pipe, a discharge-valve and piston therefor, a pilot-valve for the main valve, a spindle carrying the pilot-valve at one end and an inverted bell at the other, a tube attached to the discharge-valve and extending down beyond the end of the discharge-pipe, a fly-wheel on the tube and vanes on the spindle and on the tube, substantially as and for the purposes described.

In testimony whereof I have signed my name to this specification in the presence of two subscribing witnesses.

WILLIAM J. POOLE.
